UNITED STATES PATENT OFFICE.

GARRET SCHENCK, OF MILLINOCKET, MAINE, ASSIGNOR TO GREAT NORTHERN PAPER COMPANY, OF MILLINOCKET, MAINE, A CORPORATION OF MAINE.

FOURDRINIER MACHINE.

1,246,945.

Specification of Letters Patent. Patented Nov. 20, 1917.

Application filed April 17, 1916. Serial No. 91,523.

To all whom it may concern:

Be it known that I, GARRET SCHENCK, a citizen of the United States, residing at Millinocket, in the county of Penobscot and 5 State of Maine, have invented an Improvement in Fourdrinier Machines, of which the following is a specification.

Papermaking machines of the Fourdrinier type usually comprise, generally speaking, 10 means for forming a web involving a paper-making wire, and means for pressing and drying the web involving pressing and drying felts and drying-rolls. When the web of paper leaves the machine, it usually 15 passes to a calender.

The calendering operation is commonly performed by a stack of cold cylinders, which squeeze the thoroughly dried paper and crush down any inequalities due to 20 shives or other causes, so that the paper will have an even thickness and smooth finish. With certain very slow-running machines, a high polish may be given to one side of the paper by a single drying drum, but for 25 many kinds of paper, particularly newspaper, for which this invention is particularly designed, slow-running machines, producing a different finish on the two sides of the paper, are inapplicable, and in practice it 30 has been found necessary to put the paper through a special calendering operation. Such calendering operation causes a very substantial proportion of the breaks in the paper and consequent stoppages of the machine, 35 and in addition, injures the strength of the finished product by the high crushing pressure necessarily applied to smooth out the inequalities in the paper after it has been entirely dried.

40 This invention consists in arranging certain cylinders to act both for drying and for pressing out the inequalities and shives in the paper and give it the requisite finish. By this arrangement, the shives in the web 45 of paper are pressed out while moist, in which condition a comparatively slight pressure will reduce them to the thickness of the remainder of the sheet, and the smoothing out and finishing of the paper is obtained 50 without crushing and weakening the paper and without the loss of time and material caused by breaks at the calender.

The cylindrical surfaces of the usual drying cylinders are not sufficiently accurate to

engage adjacent drying cylinders throughout the entire length with a uniform pressure, and, therefore, such cylinders can not be used to perform the results which I obtain, and only when they are purposely rearranged relative to each other to engage 55 adjacent cylinders, and are also purposely ground to provide accurately formed complementary cylindrical surfaces, so that an even or uniform pressure will be produced throughout their entire length, will the result sought by me, be accomplished. I, therefore, avoid the employment of a calender at the end of the machine.

There is another object obtained by omitting the usual calender. At the present 70 time, fast running machines are being more and more introduced, and the faster the machine is run, the more drying cylinders are required to dry the paper, and when these additional drying cylinders are added 75 to the length of the machine, the ordinary mills now built are not long enough to receive them, and also provide room for the calender and the other necessary space at the leaving end of the machine, but with my 80 invention the space usually occupied by the calender is available for the use of extra drying cylinders.

85 My newly formed drying cylinders may be arranged in pairs, one above the other, so that there will be one line of contact or point of engagement between the cylinders of each pair, or they may be staggered with respect to each other, so that each drying cylinder will engage two adjacent drying 90 cylinders, with the exception of the end-most cylinders of the set. The latter arrangement, however, requires the cylindrical surface of each drying cylinder to be so formed as to engage complementally two 95 adjacent drying cylinders with a uniform pressure throughout the entire length, while the former arrangement requires the cylindrical surfaces of the cylinders of each pair to be so ground or complementally formed, 100 and in practice it is much easier to form two cylinders so as to complementally engage, hence I prefer to employ the arrangement where the cylinders are arranged in pairs, although in this way six drying cylinders 105 will give only three pinches to the web, while with the staggered arrangement, six cylinders will give five pinches.

I am aware that it has been proposed to provide pressing or calendering means between the drying cylinders of a Fourdrinier machine, which means was independent of 5 the drying cylinders, but, so far as I am aware, no practical embodiment of such proposition has ever been produced, and the construction set forth in this specification, is, so far as I am aware, entirely novel.

10 Figure 1 is a side elevation of a portion of a Fourdrinier machine illustrating a set of drying cylinders constructed and arranged to embody my invention.

Fig. 2 is an enlarged transverse section of 15 the machine, illustrating one pair of rolls.

Fig. 3 is an enlarged sectional view of one of the bearings.

Fig. 4 is a fragmentary detail of the control for the hydraulic jacks which are associated with the bearings for the roll. 20

Fig. 5 is a side elevation of a modified form of the invention.

Referring to Fig. 1, 10 represents the drying cylinders journaled in bearings supported by the side frames 15; and 16 the upper felt, and 17 the lower felt, which felts are associated with the drying cylinders in usual manner. 18 represents the web of paper. The drying cylinders of the set are 25 arranged one above the other in pairs, there being three pairs here shown. The cylinders of each pair are in engagement with each other at the points marked 20, a line of contact being made at such point. Each cylinder has its cylindrical surface ground to engage complementally its fellow cylinder, with accuracy, so as to exert a uniform pressure throughout the entire width of the sheet passed between them, so as to serve as calenders as well as driers. 30

These cylinders are made hollow and adapted to be heated by any suitable means, as for instance, one of the journals of each cylinder may be made tubular through which 45 steam may pass to the interior of the cylinder, and there may be supported, by a bracket 13, on the inner end of the tubular journal, a siphon pipe 14. Such heating-means does not uniformly heat the cylindrical walls of the cylinders throughout their entire area, hence the grinding of the cylindrical surfaces must be carefully performed to insure their complemental engagement. 50

55 Unless the cylinders, when heated, engage each other so as to exert an even pressure throughout their entire length, the paper will not press evenly or uniformly throughout its entire width, and will not serve as calenders as well as driers.

These newly-formed drying cylinders, or drying cylinders having calendering surfaces when arranged in engagement with each other, are adapted to be driven by any 60 usual or suitable means.

The cylinders are very heavy, weighing many tons, and it is desirable to variably reduce the pressure of the upper cylinders on the lower cylinders, due to their great weight, such variation being more or less 70 according to the work to be done. For the accomplishment of this result the journals of the upper cylinders are arranged in bearing boxes 25, see Fig. 3, adapted for sliding movement in the side-frames, and said boxes 75 are surmounted on and supported by upright jack-rods 26, of a hydraulic jack, which rods extend downward into hydraulic cylinders 27, and bear at their lower ends suitable pistons 28, which are adapted to work 80 in said cylinders. There is a pipe 29 connected with each pair of hydraulic cylinders, which are arranged at the opposite ends of each upper cylinder, see Fig. 4, having a controlling-valve 30, by which water under 85 pressure, or steam, or compressed air may be admitted to the hydraulic cylinders or allowed to escape, thereby to raise the pistons or permit them to descend.

By means of these hydraulic jacks the 90 upper cylinders may be lifted, and the range of motion is sufficient to lift them entirely free from the lower cylinder. When said upper cylinders are permitted to descend a very accurate adjustment is required to variably reduce their pressure on the lower cylinders, due to their great weight, and herein a ring-nut 31, is arranged on the threaded portion of the jack-rod 26, adapted to engage a pair of lugs 32, 32, extended inward from hubs 33, 33, pivotally supported on studs 34, 34, said hubs bearing arms 35, 35, which are extended upward, the extremities of which arms have holes through them, and a horizontally arranged bar is extended loosely through the holes in the extremities of the arms, which bar has nuts arranged on its extremities at the outside of the arms. 100

The weight of the cylinder is transmitted 110 through the ring nuts and lugs to the pivoted arms, whereupon said arms have a tendency to swing in a direction toward each other, and means are arranged on the bar to counteract this movement. As here 115 shown, there may be a nut 36 arranged on the bar at the inside of one of the arms, which obstructs its movement toward the other arm, and a spring 37 is arranged on the bar, one end of which engages the inside of the other arm, and the other end of which engages a nut 38 on the threaded portion of the bar, by which said spring may be adjusted to vary its resisting force, said spring resisting movement of the arm which 120 it engages in a direction toward the other arm. By this means of adjustment the full weight of the upper cylinder may be variably reduced as much or little as desired. 125

Furthermore, this adjusting means is in- 130

dependent of the lifting-means, so that the lifting-means may be operated to lift the cylinder without disturbing the adjustment by which the descent of the cylinder is determined. This is an advantage for it enables the adjustment to be set and thereafter maintained notwithstanding the cylinder may be repeatedly lifted.

Also associated with the upper and with the lower cylinders are strippers 40, arranged tangentially thereto and suitably supported, which are adapted to strip the web from the cylinders in case it has a tendency to adhere thereto.

Referring to Fig. 5, the drying cylinders are formed substantially the same as in Fig. 1, but are staggered with respect to each other so that they engage two adjacent cylinders, thus multiplying the number of times the paper is engaged and pressed. In this form, however, much more difficulty is encountered in grinding the cylindrical surfaces to make them conform to each other in such a manner that a uniform pressure is produced throughout their entire length when in engagement. The upper cylinders are or may be supported by adjustable bearings.

I claim:—

1. A Fourdrinier papermaking machine having a series of rotatable drying cylinders arranged in upper and lower tiers in staggered relation, each cylinder of the upper tier having a bearing surface formed complementary to the two adjacent cylinders of the other tier, bearings arranged to permit the cylinders of the upper tier to exert a substantial and uniform pressure on the cylinders of the lower tier throughout the width of the paper sheet to be passed between them, a felt for the upper drying cylinders and a felt for the lower drying cylinders, and

inders, and guiding and driving means for the same, whereby the paper may be led around the drying cylinders and between their points of engagement.

2. A Fourdrinier papermaking machine having a series of rotatable hollow drying cylinders arranged in upper and lower tiers for engagement, said cylinders having their cylindrical surfaces formed to insure complementary engagement, when heated, thereby to exert a substantial and uniform pressure throughout their engaging length, movable bearing boxes for the journals of the cylinders of the upper tier, means for lifting said upper cylinders, and adjustable means for limiting the descent of said upper cylinders to variably reduce the pressure due to the weight of the cylinders.

3. A Fourdrinier papermaking machine having a series of rotatable hollow drying cylinders arranged in upper and lower tiers for engagement, said cylinders having their cylindrical surfaces formed to insure complementary engagement, when heated, thereby to exert a substantial and uniform pressure throughout their engaging length, movable bearing boxes for the journals of the cylinders of the upper tier, hydraulic jacks for lifting said cylinders, means arranged on the jack-rods, and adjustable means adapted to be engaged by the means on the jack-rods for limiting the descent of the cylinders, thereby to variably reduce the pressure due to the weight of the cylinders.

In testimony whereof, I have signed my name to this specification, in the presence of two subscribing witnesses.

GARRET SCHENCK.
